UNITED STATES PATENT OFFICE.

ALEX M. KELSO, OF MURPHYSBORO, ILLINOIS.

LIGHT ACCELERATOR OR SWITCH.

Application filed November 10, 1925. Serial No. 68,185.

This invention relates to improvements in electric switches and is more particularly adapted to a means for accelerating the lights on a motor vehicle.

5 One of the important objects of the present invention is to provide a light accelerator wherein the same includes a switch which is arranged on the motor vehicle in such a manner as to enable the operator to have access thereto at all times, whereby the headlights on a motor vehicle may be readily and easily controlled so that the degree of illumination or candle power of the light may be controlled.

10 15 A further object is to provide a light accelerator or switch of the above mentioned character which includes a pair of stationary contacts mounted on an insulated body, one of the contacts controlling the light of the bright headlights, the other contact controlling the dimming of the lights, a slidable plunger having a contact formed on its lower end and normally in engagement with the first mentioned contact, a foot pedal being associated with the plunger for disengaging the contact carried thereby from engagement with the first mentioned contact in moving the plunger and its contact into engagement with the additional contact arranged on the insulated body for effecting the dimming of the lights.

30 35 A still further object is to provide a light accelerator of the above mentioned character which is simple in construction, inexpensive, strong and durable and further well adapted to the purpose for which it is designed.

40 Other objects and advantages of the invention will become apparent during the course of the following description taken in connection with the accompanying drawing.

In the accompanying drawing forming part of this application and in which like numerals designate like parts throughout the same:

45 Figure 1 is a diagrammatic view of the light on a motor vehicle and the wiring therefor, showing the light accelerator or switch embodying my invention associated therewith.

50 Figure 2 is an enlarged vertical sectional view through the switch, and

Figure 3 is a bottom plan view thereof.

In the drawing, wherein for the purpose of illustration is shown the preferred embodiment of my invention, my improved

light accelerator switch comprises a cylindrical body 1 of any suitable insulating material such as fibre. The cylindrical body is preferably constructed of complementary sections as shown more clearly in Figure 3, 60 and suitable transversely extending securing means 2 passing through the complementary sections to provide a unitary structure. The cylindrical body is provided with the longitudinally extending bore 3, and the 65 same is substantially rectangular in cross section.

A cylindrical face plate 4 is secured on the upper end of the cylindrical insulated body 1 and is of greater diameter than the body. 70 This plate is provided with suitable openings 5 to receive suitable fastening screws or the like whereby the face plate will be secured on the floor board of a motor vehicle within easy access of the operator, the cylindrical body being disposed below the floor board. This face plate is provided with a central opening 6 which is of a diameter greater than the diameter of the bore 3 as is clearly illustrated in Figure 2, and the purpose of this construction will be presently apparent.

75 80 85 A stationary contact 7 is secured on the bottom of the insulated cylindrical body 1 on one side of the bore 3, and the same is connected to the headlights 8 through the medium of the wiring 9 whereby the lights may be caused to burn their brightest.

An additional stationary contact 10 is secured on the bottom of the cylindrical block or body 1 at a point diametrically opposite the stationary contact 7. This last mentioned contact 10 includes a downwardly extending and tapering strip 11, the same being slightly bent so that in bottom plan, 90 the free end portion of the strip 11 will cover the bore 3. This is more clearly illustrated in Figure 3 of the drawing.

95 The stationary contact 10 is also connected to the headlights 8 by suitable wiring illustrated at 12 and associated with the circuit between this contact and the headlights is the resistance coil 13.

100 105 110 Adapted for vertical slidable movement through the bore 3 of the insulated block or body 1 is the plunger rod 14, the same being also substantially rectangular in cross section for cooperation with the rectangular shaped bore, so that the plunger will not rotate within the insulated body or block.

The lower end of the plunger is disposed laterally to provide a contact 15 for cooperation with the aforementioned stationary contact in the manner to be presently described. A foot pedal 16 is provided on the upper end of the plunger rod 14 and encircling the upper portion of the plunger rod is the expansible coil spring 17. One end of the spring engages the under side 10 of the foot pedal 16 while the lower end of said spring engages the upper end of the insulated block or body, and is confined within the opening 6 formed in the face plate 5.

15 The coil spring 17 normally holds the slideable plunger rod in its uppermost position so that the contact 15 will bridge the contact 7, and thus the circuit to the bright headlights will be closed. It is of course understood that the contact 15 is connected to the source of electric energy shown at 18 through the medium of the wiring 19, a terminal 20 of any well known construction being provided on the outer end of the lateral extension which forms the contact 15 for securing one end of the wire to said contact. The usual hand switch 21 is connected with the circuit leading from the storage battery or any other suitable source of supply to the contact 15 in the manner as clearly shown in diagram in Figure 1.

Whenever it is desired to dim the lights, the operator of the motor vehicle depresses the foot pedal 16 causing the slideable plunger rod to move downwardly through the bore 3 of the insulated body or block 1, and simultaneously the contact 15 is moved out of engagement with the contact 7, and is then brought into engagement with the laterally disposed portion 11 of the contact 10. In this manner, the lights may be readily and easily dimmed whenever necessary and will not necessitate the manipulating of the usual hand switch mounted on the instrument board, for controlling the switching of the lights from bright to dim. It is of course to be understood that the operator can use the usual light controlling switch for controlling the dimming of the headlights without necessarily having to operate a foot controlled light accelerator or switch. Also if the driver wishes to leave the lights on dim for any length of time, he can turn the switch

on the instrument board to the dimming position.

The simplicity of my improved device enables the same to be readily and easily installed in the lighting system of a motor vehicle, and will not in any way interfere with the ignition system already installed.

Furthermore, a light accelerator or switch of the above character will at all times be positive and efficient in carrying out the purposes for which it is designed.

While I have shown the preferred embodiment of my invention, it is to be understood that minor changes in the size, shape and arrangement of parts may be resorted to without departing from the spirit or scope of the invention.

Having thus described the invention, what I claim as new is:

A switch of the class described comprising a block of insulated material having a longitudinal bore, a stationary contact secured on the bottom of the block on one side of the bore, a second stationary contact secured on the bottom of the block on the other side of the bore at a point diametrically opposite the first mentioned stationary contact, said second contact having a strip of spring metal depending therefrom and being slightly inclined downwardly in a direction toward the first mentioned contact, the free end portion of the strip being disposed over the bore of the block, a plunger adapted for vertical slideable movement through the bore, a lateral extension formed on the lower end of the plunger and providing a contact adapted for cooperation with the aforementioned contacts, a foot pedal on the upper end of the plunger, an expansible coil spring encircling the upper portion of the plunger disposed between the foot pedal and the upper end of the insulated block for normally holding the lateral extension on the lower end of the plunger in engagement with the first mentioned stationary contact, said lateral extension being adapted to be moved out of engagement with the first mentioned stationary contact and into engagement with the depending spring strip of the second stationary contact when the foot pedal is depressed.

In testimony whereof I affix my signature
ALEX M. KELSO.
